UNITED STATES PATENT OFFICE

OTTO BEHIMER, OF CHICAGO, ILLINOIS, ASSIGNOR TO THE TEXAS COMPANY, OF NEW YORK, N. Y., A CORPORATION OF DELAWARE

TREATING HYDROCARBON OILS

Application filed May 18, 1927, Serial No. 192,226. Renewed October 3, 1929.

This invention relates essentially to certain novel methods of fractionating hydrocarbon oils and has special reference to certain methods of treating the evolved vapors and distillates of pressure cracking stills.

My invention contemplates carrying on the dephlegmation and fractionation of the evolved vapors, and handling the condensates, in such a way as to obtain the well known advantages of fractionating and condensing under pressure and at the same time produce a properly fractionated or stabilized gasoline or naphtha distillate. At the present time gasoline specifications call for a 96% recovery as indicated on the Standard Engler distillation flask whereas in the gasoline distillate usually taken off pressure cracking systems the percent recovery is considerably lower, for example about 92%. My invention enables the production of a suitably fractionated or rectified distillate and with a minimum of loss of liquid components in the exit gases from the system.

My invention contemplates the use of heat contained in products derived from the cracking re-action to supply the heat necessary to fractionate or rectify the distillate and in the practice of my invention a portion of the vapors is withdrawn and conducted to the rectifying or fractionating apparatus, thereby supplying the heat necessary for removing the fixed gases from the distillate. In one way of carrying on my invention the vapors from the cracking still are subjected to a primary separation as by condensation, or preferably fractionation, to form a liquid comprising the heavier constituents which it is undesirable to have in the final distillate and a lighter vapor fraction comprising essentially the hydrocarbons desired in the final gasoline or naphtha distillate together with fixed gases; a portion of the vapor fraction is conducted to a condenser and the liquid condensate is drawn off and rectified or fractionated, the heat required being supplied by the other portion of the vapor fraction.

In order to more fully disclose my invention, reference will now be had to the accompanying drawings which illustrate preferred embodiments thereof and wherein:

Figure 1 is a diagrammatic elevation partially in section of an apparatus constructed in accordance with the invention and constituting an embodiment thereof.

Figures 2 and 3 are partial views in elevation partly in section of modified or alternative apparatus.

Referring now more particularly to the apparatus shown in Figure 1, 10 designates the primary separator or fractionating column, 11 the condenser for condensing the vapor fraction from the fractionating column and 12 the fractionating column employed in treating the final condensate. The vapor product to be treated is introduced to the separator 10 through a vapor line 13 which is in communication with a pressure cracking still not shown. The separator 10 is of any suitable form but is preferably a fractionating or rectifying column containing suitable contact material or apparatus to facilitate contact of the down flowing liquid and upwardly rising vapors therein. The column may well be in the form of a bubble tower. It is shown equipped with a reflux condenser 14 interconnected with a vapor line 15 and a reflux condensate line 16. A vapor line 17 provided with a valve 18 extends from the fractionating apparatus, or more specifically from the reflux condenser 14, to a condenser 11. A pipe 19 is provided for removing the condensate formed and collected in the column 10.

A line 20 having a valve 21 serves to conduct the condensate from the coil 11 to a receiving drum 22 which is equipped with a valved gas outlet line 23 and a valved condensate outlet line 24. The line 24 is shown as terminating in a midpoint in the fractionating or rectifying column 12. This column is shown equipped with a reflux condenser 25 with an interconnecting gas line 26 and reflux condensate line 27. The reflux condenser 25 as well as the reflux condenser 14 are supplied with cooling from any suitable source and it is to be understood that the reflux condensers constitute parts of, or are adjuncts to, their respective fractionating columns and that if desired other cooling means may be supplied, such for example as

cooling coils in the upper parts of the columns 10 and 12. A gas line 36 serves to remove the gases from the system. The line 36 as well as the line 23 from the receiving drum 22 may extend to suitable gas storage tanks or to compression or absorption apparatus for recovery of any liquid constituents therein.

A branch pipe 28 having a valve 29 extends 10 from the vapor line 17 to a coil 30 in the lower part of the fractionating column 12. This coil is connected by a pipe 31 to a coil 32 mounted in suitable cooling apparatus 33, and a pipe 34 connects the coil 32 with the 15 receiving drum 22. The fractionating or rectifying column 12 may be provided with any suitable contact apparatus or material. An advantageous arrangement is to have 20 bubble trays in that portion of the tower above the point in which the pipe 24 enters and merely baffles or plates in the portion below the point of entry and above the coil 30. A valved pipe 35 is provided for conducting the rectified or fractionated distillate to 25 treating apparatus 55 for purifying or rendering it stable from the chemical standpoint, or the pipe 35 may extend to suitable storage tanks (not shown).

In practicing the invention illustrated in 30 Figure 1, the vapors from the pressure still are conducted to the rectifying or fractionating column 10 and subjected to rectification therein to form a vapor fraction which is removed through the line 15, reflux condenser 35 14 and vapor line 17. The liquid fraction is preferably returned to the cracking zone for re-treatment. The valve 18 is normally open and the vapors pass without obstruction to the condenser 11 except such portions 40 as are drawn off through the line 28, the valve 29 being opened sufficiently to permit the withdrawal of the desired portion of vapors and their admission to the coil 30. The primary separation or fractionation 45 carried on in the column 10 is preferably conducted under a material superatmospheric pressure and may well be under approximately the same pressure as that of the cracking still from which the vapors to be treated 50 are withdrawn. While the valve 18 may be used as a pressure reducing valve to reduce the pressure in the condenser 11, it is generally preferable to maintain the high pressure through the condenser 11. The condensate 55 formed in the condenser 11 together with the contained gases passes through the pipe 20 into the receiving drum 22. The valve 21 may be used as a pressure reducing valve to reduce the pressure to a greater or 60 lesser extent in the receiving drum 22. The condensate collected in the receiver is fed through the line 24 into the fractionating column 12. The valve in the line 24 may serve as a means for dropping the pressure 65 a further amount in the fractionating col-

umn. The condensate thus introduced into the fractionating column is subjected therein to fractionation or rectification and the heating coil 30 serves to heat the final or ultimate condensate formed in the column and insure that practically all of the gaseous constituents are removed therefrom. While the rectifying operation carried on in the column 12 may be conducted at substantially the pressure obtaining in the condenser 11 or the fractionating column 10, such a procedure is not to be recommended in view of the difficulty encountered in thoroughly removing the fixed gases from the liquid condensate at higher pressures. It is therefore desirable 70 to carry on the rectifying of the distillate in the column 12 at a pressure materially reduced from that obtaining in either the fractionating column 10 or the condenser 11 and in fact it is generally preferable to maintain the column 12 under pressures approaching atmospheric. However, it is generally desirable to maintain some pressure above atmospheric in the column 12 because this pressure facilitates the removal of the gases 80 and liquids from the column and in cases where it is desired to subject the distillate to chemical treatment immediately after rectification, as in apparatus 55, the pressure in the column may be advantageously used to 85 force the distillate through the treating vessels. In cases where the cracking operation is carried on under several hundred pounds pressure, for example, and a similar pressure is maintained in the fractionating column 10 and condenser 11, the column 12 may be 90 conveniently held under pressures ranging from about 25 to 50 pounds.

The vapors and gases in the coil 30 together with condensate formed therein are conducted by the pipe 31 to the cooling coil 32 and passed thence through the line 34 into the receiving drum 22. In some cases the cooling coil 32 may be dispensed with but ordinarily there will not be sufficient cooling, 105 by the heat exchange between the coil 30 and the liquid in the bottom of the fractionating column 12, to condense all the condensable constituents passing through the coil 30 and it is generally desirable to further cool the 110 fluids discharged from the coil 30 so that substantially all the condensable fractions may be liquified. It is of course desirable to have the gases passing out through the line 23 and also the gases leaving through the pipe 36 in as dry a condition as possible. Ordinarily the gases leaving through the pipe 23 will contain some condensable fractions but if adequate cooling be supplied to the 115 column 12, the gases removed from the line 36 may be substantially dry.

In the apparatus shown in Figure 2, the outlet pipe 20 from the condenser 11 extends directly to a fractionating or rectifying column 37. The line 20 is shown as entering 120

the column at an intermediate point. The pipe 28 operates to conduct hot vapors into a heating coil 38 positioned in the fractionating column and the coil 38 is provided with an outlet pipe 39 which extends to a midpoint in the rectifying column and operates to discharge into the column vapors together with any condensate formed in the coil 38. The tower is shown equipped with a reflux condenser 40 with an interconnecting vapor line 41 and reflux condensate line 42. The gases are withdrawn through a pipe 43 and the rectified liquid is removed through a line 44. This particular type of equipment is well adapted for operations in which it is desired to carry on the fractionation in the column 37 under material superatmospheric pressures and this system is furthermore well adapted for operations in which the liquid condensate drawn off through pipe 44 is forced through treating apparatus 55 containing treating materials for purifying and stabilizing the distillate.

In the apparatus illustrated in Figure 3, the outlet pipe 20 extends to a receiving drum or chamber 45 and the pipe 28 is in communication with a perforated pipe or coil 46 positioned in the bottom of the drum 45 so that the hot vapors and gases withdrawn from the pipe 17 may be introduced directly into the distillate to be stripped or fractionated. The vapors evolved in the receiving drum are fractionated or rectified in a column 47 which is connected to the drum by means of a vapor line 48 and a reflux condensate line 49. The rectifying column 47 is shown equipped with a reflux condenser 50 with an interconnecting vapor line 51 and a reflux condensate line 52. The gases are withdrawn through a pipe 53 and the rectified condensate is drawn off from the rectifying apparatus through a line 54. The method of operation illustrated in Figure 3 has the advantage of efficient heat exchange of the hot vapors by direct contact with the liquid to be rectified and also makes possible the utilization of the vapors and gases introduced through the line 28 to act as a carrier for removing the fixed gases from the liquid. This method has, however, a disadvantage as compared with the methods shown in Figures 1 and 2 since when the vapors and gases introduced through line 28 are thus admitted into direct contact with the liquid being rectified, there may be opportunity for some entrainment or absorption of gas in the liquid collected in the receiving drum. However, this tendency toward gas absorption is minimized by reason of the heated condition of the gases introduced.

Obviously many modifications and variations of the invention, as hereinbefore set forth, may be made without departing from the spirit and scope thereof, and therefore only such limitations should be imposed as are indicated in the appended claims.

What I claim is:

1. In the treatment of hydrocarbon oils, the process that comprises removing vapors from a pressure still and while still maintaining them under pressure, effecting a primary separation thereof into a liquid and a vapor fraction, subjecting a portion of the vapor fraction to cooling to form a condensate, subjecting this condensate to rectification to form a rectified liquid while passing the other portion of said vapor fraction into heat exchange with the ultimate condensate of the rectification. 70

2. In the treatment of hydrocarbon oils, the process that comprises removing vapors from a pressure still and while still maintaining them under pressure, effecting a primary separation thereof into a liquid and a vapor fraction, subjecting a portion of the vapor fraction to cooling to form a condensate, subjecting this condensate to rectification under reduced pressure to form a substantially dry gas and a rectified liquid while passing the other portion of said vapor fraction into heat exchange relation with the ultimate condensate of the rectification. 80

3. In the treatment of hydrocarbon oils, the process that comprises removing vapors from a pressure still and while still maintaining them under pressure, effecting a primary separation thereof into a liquid and a vapor fraction, subjecting a portion of the vapor fraction while still under pressure to cooling to form a condensate, reducing the pressure on the condensate, subjecting this condensate to rectification under the reduced pressure to form a rectified liquid while passing the other portion of said vapor fraction into heat exchange relation with the ultimate condensate of the rectification. 95

4. In the treatment of hydrocarbon oils, the process that comprises conducting vapors from a pressure still to a rectifying column and subjecting the vapors to rectification therein while still under a material superatmospheric pressure, removing evolved vapors from the rectifying column and subjecting a portion of them to cooling to form a condensate, introducing the condensate to a rectifying column and subjecting the condensate to rectification therein to form a substantially dry gas and an ultimate condensate while passing the other portion of the vapors from the first rectifying column in heat exchange relation with the ultimate condensate of the second rectifying column. 100

5. In the treatment of hydrocarbon oils, the process that comprises conducting vapors from a pressure still to a rectifying column and subjecting the vapors to rectification therein while still under a material superatmospheric pressure, removing evolved vapors from the rectifying column and subjecting a portion of them to cooling to form a condensate, introducing the condensate to a 115

second rectifying column and subjecting the condensate to rectification therein to form a substantially dry gas and an ultimate condensate while passing the other portion of the 5 vapors from the first rectifying column through a conduit in heat exchange with said ultimate condensate of the second rectifying column.

6. In the treatment of hydrocarbon oils, 10 the process that comprises conducting vapors from a pressure still to a rectifying column and subjecting the vapors to rectification therein while still under a material superatmospheric pressure, removing evolved 15 vapors from the rectifying column and subjecting a portion of them to cooling to form a condensate, introducing the condensate to a second rectifying column and subjecting the condensate to rectification therein to 20 form a substantially dry gas and an ultimate condensate while passing the other portion of the vapors from the first rectifying column through a conduit in heat exchange with said ultimate condensate of the second rectifying column to heat the condensate, and discharging the fluids from said conduit into the second rectifying column at a point therein removed from the ultimate condensate.

7. In the treatment of hydrocarbon oils, 30 the process that comprises conducting vapors from a pressure still to a rectifying column and subjecting the vapors to rectification therein while still under a material superatmospheric pressure, removing evolved 35 vapors from the rectifying column and subjecting a portion of them to cooling to form a condensate, collecting the condensate in a receiver wherein separation of gas and liquid constituents takes place, introducing the 40 liquid from the receiver into a rectifying column and subjecting the liquid to rectification therein to form a substantially dry gas and an ultimate condensate while passing the other portion of the vapors from the first 45 rectifying column through a conduit in heat exchange with the ultimate condensate formed in the second rectifying column and discharging the fluids from said conduit into the receiver.

50 8. In the treatment of hydrocarbon oils, the process that comprises conducting vapors from a pressure still to a rectifying column and subjecting the vapors to rectification therein while still under a material super- 55 atmospheric pressure, removing evolved vapors from the rectifying column and subjecting a portion of them to cooling to form a condensate, collecting the condensate in a receiver wherein separation of gas and liquid 60 constituents takes place, introducing the liquid from the receiver into a rectifying column and subjecting the liquid to rectification therein to form a substantially dry gas and an ultimate condensate while passing 65 the other portion of the vapors from the first

rectifying column through a conduit in heat exchange with the ultimate condensate formed in the second rectifying column, conducting the fluid from said conduit to a cooler wherein the fluid is subjected to cooling and discharging the cooled fluid into the receiver. 70

9. In the treatment of hydrocarbon oils, the process that comprises conducting vapors from a pressure still to a rectifying 75 column and subjecting the vapors to rectification therein while still under a material superatmospheric pressure, removing evolved vapors from the rectifying column and subjecting a portion of them to cooling 80 to form a condensate, collecting the condensate in a receiver wherein separation of gas and liquid constituents takes place, introducing the liquid from the receiver into rectifying column and subjecting the liquid to 85 rectification therein to form a substantially dry gas and an ultimate condensate while passing the other portion of the vapors from the first rectifying column through a conduit in heat exchange with the ultimate condensate contained in the second rectifying 90 column, conducting the fluid from said conduit to a cooler wherein the fluid is subjected to cooling and discharging the cooled fluid into the receiver, removing as a rectified liquid the ultimate condensate collected in the second rectifying column and taking off the substantially dry gas from the receiver and the second rectifying column. 95

10. In the treatment of hydrocarbon oils, 100 the process that comprises removing vapors from a pressure still and, while still maintaining them under pressure, effecting a primary separation thereof into a liquid and a vapor fraction, passing vapors derived from 105 such separation in heat exchange, but not in direct contact, with condensate in the lower part of a rectifying tower to thereby heat said condensate and effect partial condensation of said vapor, passing the partially condensed vapor to a cooler to be subjected 110 therein to further cooling and condensation, directing the cooled product into said rectifying tower and subjecting it to rectification therein while cooling the upper part of the 115 tower and withdrawing the rectified liquid from the lower part of the tower.

In witness whereof I have hereunto set my hand this 16th day of May, 1927.

OTTO BEHIMER. 120
